UNITED STATES PATENT OFFICE

2,180,907

TUBULAR WATER HEATER OR GEYSER

John Ernest Neale and Albert Guest,
Coventry, EnglandApplication March 21, 1939, Serial No. 263,286
In Great Britain June 10, 1938

5 Claims. (Cl. 122—355)

This invention relates to pipe systems, for geysers, of the kind including at least two superposed, substantially horizontal layers of substantially parallel pipes arranged between headers, with approximately the same number of pipes in each layer, our main object being to provide a compact and highly efficient construction thereof.

According to the main feature of the invention, the arrangement is such that the water in one of the layers (preferably in the lowest layer, or in the lower layer, when there are only two, as is preferred) will flow in parallel (i. e., in multiple paths) in one direction in some of the pipes and in parallel (i. e., multiple paths) in the other direction in the remainder, while in the other or another layer the water will flow in parallel in the same direction in all the pipes, some of the pipes at least carrying radiating fins which preferably embrace all the pipes.

Preferably one set of pipes in the said one layer (in which the water flows in one direction) are bent out of the common plane of the layer at one end, these bent ends being connected to an inlet header and the opposite ends by a double header to the inlet ends of the other set of pipes in this layer. Instead of the said opposite ends also being bent out of the common plane of the layer, the said inlet ends of the other set of pipes are preferably so bent, as is actually illustrated in the accompanying drawing, in which case the pipes of both sets can be identical.

In the accompanying drawing:

Figure 1 is a perspective view of half of one construction, according to the invention, with the header members shown detached, the section being on the line I—I of Figure 2;

Figure 2 is an end elevation thereof; and

Figure 3 is a longitudinal section taken mainly on the line III—III of Figure 1.

In the construction illustrated, there are two parallel, superposed layers 11, 12 of pipes arranged horizontally, the pipes of one layer being staggered (in plan) with reference to those of the adjacent layer, as is indicated in Figure 2. There is a cross pipe or header 13 of larger bore, disposed at one end of the bottom layer 11, to which the water is fed by the inlet 14, and this header is connected to each alternate pipe of the bottom layer. The ends of this set of pipes may be bent downwardly for this purpose, as shown at 15, and from an inspection of Figure 2 it will be observed that there are seven such pipes. At the other end of this layer is a cross pipe or double header 16 to the upper part of which is connected

the ends 15a of the set of pipes carrying the inlet water. The lower part of this double header is connected to the other set of pipes of the bottom layer, the ends of the latter pipes being bent downwardly as shown at 17. In like manner the remote ends 17a of these latter pipes (of which there are eight in the construction illustrated) are connected to the lower portion of another transverse pipe or double header 18 and the upper part thereof is connected to the adjacent ends of the upper layer 12 of pipes. The remote ends thereof are connected to a cross pipe or header 19 of relatively-large section which in turn is connected to the water outlet 20.

The direction of the water flow is indicated by arrows, and it will be evident that the rate of flow in the upper layer 12 will be approximately only half the rate of flow in the lower layer, as there are fourteen pipes in the upper layer as against seven and eight in the two sets of pipes in the lower layer.

It is particularly desirable that at least the lower layer of pipes should carry radiating fins or the like, such as are indicated at 21. These may consist of a plurality of transverse strips with holes in them through which the pipes of the lower layer 11 extend, such strips being soldered to the pipes to assist in making a good connection, with or without flanges or the like extending along the pipes. They serve for spacing the pipes from one another in addition to the pipes being held at their ends in spaced relation. Furthermore, the strips may bear against the underside of the upper layer of pipes, or, as is illustrated, be pierced to receive these and thus assist in spacing the pipes of the upper layer above the pipes of the lower layer. A few strips 21a may be mounted on the bent ends 15 and 17 of the two sets of pipes in the lower layer 11.

In this way we can provide a very compact pipe system for a geyser and one which in practice is economical of the heating medium, which latter is preferably disposed close up to the pipe system so that the latter will be heated by direct contact with the flames.

What we claim as our invention and desire to secure by Letters Patent of the United States is:

1. A pipe system, for a geyser, including two superposed, substantially horizontal layers of substantially parallel pipes, with approximately the same number of pipes in each layer, said pipes arranged to extend between headers, said pipes and headers being arranged so that the water in the lower layer will flow in multiple paths in one direction in some of the pipes and in multiple

paths in the opposite direction in the remainder, while in the upper layer the water will flow in multiple paths in the said one direction in all the pipes, and radiating fins embracing the pipes.

5. A pipe system, for a geyser, including at least two superposed, substantially horizontal layers of substantially parallel pipes with approximately the same number of pipes in each layer, said pipes arranged to extend between headers, 10 said pipes and headers being arranged so that the water in one of the layers will flow in multiple paths in one direction in some of the pipes and in multiple paths in the opposite direction in the remainder, the adjacent ends of one set of pipes 15 in this layer being bent out of the common plane of the layer for connection to an inlet header, while in another layer the water will flow in multiple paths in the same direction in all the pipes.

3. A pipe system, for a geyser, including two superposed, substantially horizontal layers of substantially parallel pipes with approximately the same number of pipes in each layer, radiating fins carried by some of the pipes, an inlet header connected to each alternate pipe in one layer, the 25 adjacent ends of these alternate pipes being bent out of the common plane of the layer, a double header interconnecting the other ends of these alternate pipes to the adjacent ends of the remainder of the pipes in this layer, and a double 30 header interconnecting the remote ends of the said remainder of the pipes in the said one layer to the adjacent ends of all the pipes in the other layer.

4. A pipe system, for a geyser, including at

least two superposed, substantially horizontal layers of substantially parallel pipes, with approximately the same number of pipes in each layer, said pipes arranged to extend between headers, some of said pipes in one of the layers 5 having their ends bent out of the common plane of the layer and connected to an inlet header so that the water will flow in multiple paths in one direction in this set of pipes, and the rest of the pipes in this layer having their other ends bent out of the said common plane and connected to the adjacent ends of the first set of pipes through a double header, so that the water in the second 10 set of pipes will flow in multiple paths in the opposite direction in the second set of pipes, while in another layer the water will flow in multiple paths 15 in the same direction in all the pipes.

5. A pipe system, for a geyser, including two superposed, substantially horizontal layers of substantially parallel pipes with approximately the same number of pipes in each layer, said pipes arranged to extend between headers, and radiating fins carried by the pipes, said pipes and headers being arranged so that the water in the lower 20 layer will flow in multiple paths in one direction 25 in approximately half the pipes of the layer and in multiple paths in the opposite direction in approximately the other half, while in the upper layer the water will flow in multiple paths in the said one direction in all the pipes at approximately 30 half the speed of flow in the lower layer.
